UNITED STATES PATENT OFFICE.

JAMES SHAW, OF PROVIDENCE, RHODE ISLAND.

PORFOLIO.

Specification of Letters Patent No. 15,150, dated June 17, 1856.

To all whom it may concern:

Be it known that I, JAMES SHAW, of Providence, in the county of Providence and State of Rhode Island, have invented a new and improved portfolio in which music-sheets, maps, engravings, &c., may be secured successively in a substantial manner and be preserved equally as well as if they were bound in the usual mode; and I do hereby declare that the following is a full, clear, and exact description of the same, reference being had to the annexed drawings, making a part of this specification, in which—

15 Figure 1, is a view of the inner side of my improvement in an open state. Fig. 2, is a longitudinal section of the roller of the same, a portion of the covers being shown; *x*, *x*, Fig. 3, shows the plane of section. 20 Fig. 3, is a transverse section of the same, (*y*), (*y*), Fig. 1, showing the plane of section. Fig. 4, is also a transverse section of the same, (*z*), (*z*), Fig. 1, showing the plane of section.

25 Similar letters of reference indicate corresponding parts in the several figures.

A, *A*, represents the covers of the port-folio, which are connected together and constructed in the usual manner.

30 *B*, represents a roller, which may be constructed of wood. This roller is permanently attached to the back of the port-folio, or to the inner side of the leather, (*a*), or other material by which the covers, *A*, *A*, are connected. The roller is equal in length to the covers, *C*, and has a longitudinal groove, (*b*), cut in its entire length. And also has grooves, (*c*), cut in its circumferentially at equal distances apart. Three 35

40 grooves, (*c*), are represented in Figs. 1 and 2, but more may be used if necessary. The longitudinal groove, (*b*), is cut in the roller near one of the covers, *A*. In the grooves,

(*c*), metallic rings, (*d*), are fitted. These rings are not fitted tightly in the grooves 45 (*c*),—that is, at the outer or exposed side of the roller, as the grooves are wider and deeper than the thickness of the rings so that threads, (*e*), may pass around the rings, as shown clearly in Fig. 2. At the back part 50 of the roller, however, where the leather, (*a*), is attached to it, the rings are fitted tightly in the grooves, (*c*), as shown in Fig. 3, and the rings are attached to the roller so that they cannot turn therein. The diameter of the roller, *B*, should of course 55 vary with the thickness and length of the port-folio.

The music sheets, maps, engravings or other articles, designated by *D*, are secured 60 within the port-folio, by passing a needle containing the thread or fine cord, (*e*), underneath the rings, (*d*); the needle being fitted in the groove, (*b*), so that it may pass underneath the rings, as shown in red, Fig. 65 2; the needle is then passed through the sheets so that the sheets will be secured to the several rings; the thread passing around the rings as shown clearly in Fig. 2. Single sheets are folded or a narrow strip is 70 turned over at their back edges, so that they may be attached in the same way as double ones.

I do not claim separately or in itself considered the roller, *B*; but 75

I claim—

The roller, *B*, attached to the covers, *C*, *C*, provided with the grooves, (*b*), (*c*), and rings, (*d*), which are fitted in the grooves, 80 (*c*), substantially as described for the purpose set forth.

JAMES SHAW.
